UNITED STATES PATENT OFFICE.

PHILIP G. MOOD, OF DUGGER, INDIANA.

RAIL TIE AND FASTENER.

1,425,125.

Specification of Letters Patent. Patented Aug. 8, 1922.

Application filed May 17, 1922. Serial No. 561,653.

To all whom it may concern:

Be it known that I, PHILIP G. Mood, a citizen of the United States, residing at Dugger, in the county of Sullivan and State 5 of Indiana, have invented certain new and useful Improvements in Rail Ties and Fasteners, of which the following is a specification, reference being had to the accompanying drawings.

10 The present invention has for its purpose the provision of a metallic tie, which is hollowed out or cut away centrally and at its ends, for the purpose of lightening the tie, and to economize in metal, and at the same 15 time enable a tie to be constructed relatively cheap, and yet provide strength and durability.

Another purpose is to provide a tie of this character, which is not too stiff, but on 20 the other hand will give in order to withstand the vibrations as a result of rolling stock passing over the rails.

It is to be understood that the particulars herein given are in no way limitative and 25 that while still keeping within the scope of the invention, any desired modifications of detail and desired proportions may be made in the apparatus according to circumstances.

The invention comprises further features 30 and combination of parts, as will be herein-after set forth, shown in the drawings and claimed.

In the drawings:—

Figure 1 is a perspective view of a tie 35 constructed in accordance with the invention;

Fig. 2 is a plan view;

Fig. 3 is a cross sectional view on line 3—3 of Figure 2;

40 Figure 4 is a horizontal sectional view on line 4—4 of Figure 1, showing the arrangement of the key;

Figure 5 is a view of a modified form of tie and rail fastener, showing the undercut portion of the recess eliminated.

45 Figure 6 is a perspective view of one end of a tie, showing the recesses 7 the same width throughout their height;

Figure 7 is a detail perspective view of a 50 modified form of rail fastener.

Referring to the drawings, 1 designates the body of the tie, which may be any suitable or requisite length, thickness and width.

The tie is constructed of metal, and has its 55 central portion cut away as shown at 2, to not only economize in metal, but also for the

purpose of lightening the body of the tie. The ends of the tie are also cut away transversely as shown at 3. By providing these cut away portions, the tie may be easily 60 handled to save unnecessary labor and time.

The upper face of the tie is provided with transverse depressions 4 for the reception of the bases of the rails. The opposite sides of the tie have cavities 5, the bottoms of 65 which have transverse grooves 6.

The tie is also provided with recesses 7, at diagonal opposite portions of the ends of the tie. The lower portions of the recesses 7 are undercut, as at 8, for the reception of the heads 9 of the rail fasteners 10. The upper ends of the rail fasteners 10 also have heads 11, which overlie the bases of the rails, to secure the rails in position. Certain faces of the heads at the lower ends of 75 the rail fasteners 10 are provided with transverse grooves 12, which are engaged by keys 13 which pass through openings 14 of the tie, that is to say adjacent where the cavities or recesses 5 are located. The keys also engage the grooves 6. By this construction and arrangement of tie and rail fasteners, the rails are prevented from displacement upwardly and laterally, that is excessively. 80 As shown in the drawings, if the heads at 85 the lower ends of the rail fasteners are eliminated, as well as the undercut portions of the recesses 7, then the keys themselves will retain the rail engaging elements in position, without depending upon the shoulders of the undercut portions of the recesses. 90

The invention having been set forth, what is claimed is:—

1. A combined tie and rail fastener comprising a tie body, each end thereof having a depression on its upper face for the reception of the base of the rail, and provided with diagonal opposite perpendicular recesses, the lower ends of said recesses being enlarged, rail holding elements engaging said recesses and having enlargements at their lower ends to engage the enlarged lower ends of the recesses to secure the elements against displacement upwardly, the 100 upper ends of the elements having heads to overlie the base of the rail, and transversely disposed keys engaged through the end of the tie and across the lower enlarged ends of 105 the recesses to retain the enlargements of 110 the elements in position and prevent their outward displacement.

2. In a combined tie and rail fastener, a tie body, upon and adjacent each end of which a rail is adapted to rest, said body adjacent each end being provided with 5 diagonal opposite perpendicular recesses, which open laterally upon the longitudinal side faces of the tie body, rail holding elements insertible into engagement with said recesses from the longitudinal side faces of the tie body, the lower ends of said rail holding elements having shoulders, and keys arranged longitudinally with the tie and transversely of the lower ends of the recesses and engaging with said shoulders to retain the elements in position, the opposite 15 ends of the tie body and the central portion thereof being cut away to permit the keys to be inserted longitudinally of the tie body, the keys of each end of the tie body extending in directions toward each other. In testimony whereof I hereunto affix my 20 signature.

PHILIP G. MOOD.
